MACHINE FOR MAKING HATBOXES AND THE LIKE FROM FLAT-FOLDED BLANKS

Heinz Ahlmeyer, Orangeburg, and Whitney D. Sherman, West Nyack, N. Y., assignors to Robert Gair Company, Inc., New York, N. Y., a corporation of Delaware

Application July 13, 1953, Serial No. 367,444

6 Claims. (Cl. 93—55.1)

The invention relates to a machine for setting up and finishing paperboard hat boxes and the like from flat-folded blanks. It has special application in the manufacture of certain types of boxes such as hat boxes and covers therefor of round, oval or octagonal form. In such boxes, a series of flaps project from one side of a continuous paperboard band comprising either the body or the cover flange of the box. The box bodies and cover flanges can be glued in the box makers' plants and shipped in flat-folded form, together with the end pieces for the box bottoms and cover tops, to customers who may then complete the manufacture of the boxes and covers. The boxes and covers are of non-folding types, and in such a case the objective is to perform the maximum number of manufacturing steps at the box makers' plants so as to be able to employ the simplest form of machinery and less experienced operators at the customers' plants.

Summary

In accordance with our invention, as applied for example to setting up and finishing hat boxes of the usual oval form, the side wall of the box is in the form of a continuous paperboard band made by lapping and gluing together the ends of a substantially rectangular blank. The lapped and glued blank is scored in two places and folded flat along the score lines for shipment to the customer's plant together with the end pieces as aforesaid, these being in the form of flat oval blanks. To set up the box the series of flaps at one side of the band are bent inwardly at right angles to the body of the band, and an end-piece is glued to the flaps. Preferably a second end-piece is glued to the other side of the flaps, in which case the flaps are held between the two end-pieces, out of view. The machine which we have devised for facilitating these operations comprises a forming member having an oval-shaped depression to receive the end-pieces and to receive and shape the base of the continuous paperboard band, a guide ring having an oval opening in it, means for producing relative movement between the paperboard band and the guide ring to cause the latter to surround and shape the paperboard band at its open end, a pressure plate shaped to conform closely with the inner walls of the shaped band and arranged to pass through the guide ring while the latter holds the open end of the paperboard band in position to receive the pressure plate within it, and means for producing relative movement between the forming member and pressure plate to bring the latter within the oval depression of the forming member.

The guide ring has fingers for engagement with the inside of the open end of the paperboard band and the pressure plate has slots in its periphery through which the fingers pass when the pressure plate enters through the guide ring into the open end of the paperboard band.

Other features and advantages of our invention will appear as the description proceeds.

Description

In the drawings we have illustrated a machine to show the best mode contemplated by us of carrying out our invention as applied to the manufacture of bodies and cover flanges of a hat box and the like of generally oval or octagonal form.

Fig. 1 is a side elevational view of the machine.

Fig. 2 is a top plan view of the turret table of the machine, taken approximately as indicated at 2—2 in Fig. 1.

2

Fig. 3 is a vertical cross-sectional view, to an enlarged scale, taken on the line 3—3 of Fig. 2 with the guide ring in lowered position to shape the open end of the paperboard band preparatory to entry of the pressure plate.

5 Fig. 4 is a view similar to Fig. 3 showing the parts in the position occupied at the conclusion of the pressure-applying operation.

Fig. 5 is a top view of the guide ring and associated guide bar (see 5—5, Fig. 1).

10 Fig. 6 is a top view of the pressure plate and associated guide bar.

Fig. 7 is a detail vertical cross-sectional view on the line 7—7 of Fig. 5.

Fig. 8 is an exploded view of the box parts.

15 Fig. 9 is an enlarged detail vertical cross-sectional view taken on the line 9—9 of Fig. 2.

Fig. 10 is an enlarged detail vertical cross-sectional view taken on the line 10—10 of Fig. 2.

20 Fig. 11 is an enlarged detail view similar to the lower left-hand corner of Fig. 4 but showing the formation of a box cover.

Fig. 12 is a top view of a modified forming member used for setting up an octagonal box.

25 Referring to Figs. 1 and 2, the operating elements of our machine are mounted on a suitable frame 15 having a table support 16 in which are journaled a series of rollers 17 and a spindle 18 carrying a turret table 19. The turret table rotates intermittently around spindle 18 as an axis and is supported in proper alignment by means of the aforesaid rollers 17 bearing against the under surface of the table. The center bearing for the turret table 19 is provided by a sleeve bearing 20 having a flange 21 at its lower end bolted to the table. A collar 22 fixed to spindle 18 completes the turret table mounting assembly.

30 At the rear of frame 15 (to the left as viewed in Fig. 1) is a vertical support 23. Mounted on vertical support 23 and spindle 18 is a beam 24 to which are fixed a series of vertical sleeves 25 through which slide rods 26, 26 and 27, 27 fixed to the guide ring and pressure plate to be described.

35 The principal operating elements of our machine comprise a forming member 28 having a depression, such as the oval depression 29, to receive a flat paperboard end piece A and to receive and shape the base of a continuous 40 paperboard band B, a guide ring 30, means such as the air cylinder 31 for producing relative movement between the paperboard band and the guide ring to cause the guide ring to surround and shape the paperboard band at its open end, a pressure plate 32 shaped to conform closely with the inner walls of the shaped band and arranged to pass through the guide ring 30 while the latter holds the open end of the paperboard band in position to receive the pressure plate within it, and means such as the air cylinder 31 for producing relative movement 45 between the forming member 28 and pressure plate 32 to bring the pressure plate within depression 29 of the forming member.

50 In the preferred construction illustrated, there are four identical forming members 28 arranged around the turret table 19 in such a fashion that, as the table revolves, each one in turn is presented in the same relative position to the guide ring and pressure plate 32 at the operating station shown in Fig. 1.

55 The construction of forming members 28 and their mounting on table 19 will now be described in greater detail with reference to Figs. 3, 4, 9 and 10. The forming members themselves may be built up of wood in one or more layers resting on sheet metal base 33. A pair of pins 34 have reduced portions 35 extending through

60 aligned openings in the forming member and its base plate 33. These elements of the forming member are clamped together between the shoulder at the reduced portions 35 of pins 34 and nuts 36. Table 19 is drilled as at 37 to receive pins 34 and hold the forming members in correct position on the table. We prefer to use sponge rubber pads 53 between the forming members and the table 19 to insure proper alignment between the pressure plate and base plate 33 of the forming member and thereby to obtain substantially uniform gluing pressure around the entire periphery of the box.

65 At the edge of the table 19 opposite each of the form-

ing members 28, are indexing locks 38, each of which is engaged in turn by an indexing latch 39 pivotally mounted at 40 to the frame (Figs. 1 and 2). As the table 19 is rotated, latch 39 passes over the inclined shoulder 41 of lock 38 and drops into the notch 42, indexing the adjacent forming member 28 directly beneath the guide ring 30 and pressure plate 32. Suitable means are provided for releasing the indexing latch 39 such as that comprising the rod 43 attached to latch 39 at one end and pivotally secured at the other to one arm of bell crank lever 44 pivoted to the frame, the other end of the bell crank lever being pivotally secured to a rod 45 extending through the beam 24 and pivotally secured as at 46 to the operating finger 47 pivoted at 48 at the end of beam 24 and positioned to be readily accessible to an operator standing at the front of the machine. Suitable means are provided for rotating turret table 19 by power or hand, such as the handles 49 conveniently located near the periphery of the table between the forming members.

Details of the construction and mounting of the guide ring and pressure plate assembly will be described with particular reference to Figs. 3 to 7 inclusive. Guide ring 30 may be constructed of one or more layers of wood in which is formed an oval opening 50 or an opening which otherwise corresponds to the shape of the particular box to be formed. This opening is flared outwardly as at 51 on the under side of the guide ring, and in our preferred construction a pair of inclined guide fingers 52 are secured to the under side of guide ring 30 for engagement with the outside of the open end of the paperboard band B adjacent the fold line *f* thereof to gather the open end within the confines of the guide ring as the guide ring approaches its position surrounding and shaping the paperboard band at its open end. It may be observed here that when the lapped and glued blank is folded flat for shipment, the paperboard stock takes a "set" in its folded form so that when opened into substantially oval form for gluing up the box in its final set-up condition, there is a certain amount of resistance to shaping of the band, this resistance being encountered particularly at the fold lines *f* due to what is commonly referred to in the trade as being the "tight" of the paperboard stock. Therefore, when the band B reaches the operating station shown in Fig. 1, its upper edges tend to flare outwardly at the fold line. However, the fingers 52 engage the band at these points and serve to gather the open end within the confines of the guide rings as has been described. The guide ring assembly is completed by rods 26, bushings 54 and a guide bar 55. Nuts 56 and bushings 54 serve to clamp the guide bar 55 in spaced relation to the guide ring. Guide bar 55 is provided with openings 57, 57 and 58 for the rods 27 and piston rod 59 respectively.

Pressure plate 32 (Figs. 3, 4 and 6) is fastened to the end of piston rod 59 of air cylinder 31 mounted on beam 24. Clamped between the shouldered lower end of piston rod 59 and a plate 61 is a guide bar 60 to the ends of which are secured the guide rods 27. When the operating parts are in the positions shown in Figs. 1 and 3, the guide ring 30 by means of the bar 55 fixed thereto is carried by bushings 62 associated with the guide bar 60. Thus, in these positions the guide ring 30 is supported on the pressure plate assembly which in turn is carried by piston rod 59.

The operating elements are actuated by pressure cylinder 31 and associated control mechanism comprising air conduits 63 and 64 leading from the upper and lower ends respectively of the air cylinder 31 to a four-way valve 65 controlled by handle 66. Air cylinder 31 may be of conventional construction employing a double acting piston connected to the piston rod 59. Valve 65 may also be of conventional construction and is connected to a suitable source of compressed air supply (not shown). Actuation of the valve serves to move the piston rod 59 alternately up and down according to the known method of operation of such mechanisms.

In our preferred construction the guide ring 30 has a series of fingers 67 for engagement with the inside of the open end of the paperboard band, and the pressure plate 32 has slots 68 in its periphery through which the fingers 67 pass when the pressure plate passes through the guide ring and enters the open end of the paperboard band. The form of fingers 67 may best be seen in Figs. 5 and 7. They have flanges 69 for attachment to

the upper side of the guide and the lower ends of the fingers are tapered as at 70 for cooperation with the flaring entrance portion 51 of the guide ring in gathering the open end of paperboard band B within the confines of the guide ring as the latter is lowered into the position shown in Fig. 3.

Also in our preferred construction we provide a pair of pins 71 (Figs. 2 and 10) which are resiliently supported as by means of flat springs 72 within the depression 29 of the forming member 28 for engagement with alignment notches 73 in the end pieces A and C. Springs 72 are secured, as shown, to the under side of the base 33 of the forming member and pad 53 may be cut out to provide clearance for the springs which hold the pins 71 in raised position. When the pressure plate reaches the lowermost position shown in Fig. 4, pins 71 may be pushed down slightly against the resistance of springs 72 so as not to interfere with the action of the pressure plate.

Operation

In Fig. 2 the legends indicate the four operating stations of the machine. The number of operators who will be used for each machine will depend upon the requirements of the particular plant and the judgment of the management. We think it is desirable to have three operators, in which case an operator will be stationed at each of operating stations 1, 2 and 3. There will be no operator at station 4. At station 1, the oval end piece A is placed in the bottom of depression 29 of the forming member. This end piece will first have been prepared by applying glue around the upper outside edge thereof. This also is the station at which the finished box or cover is removed at the end of a complete cycle of operation. Thus the steps performed by the operator at station 1 are (a) removal of the finished article, and (b) insertion of the glued end piece A (glue side up). Performing operation (b) the operator sees that notches 73 of end piece A properly engage pins 71. These pins perform two functions. First, they insure that the major and minor axes of the oval and piece coincide with the major and minor axes of the oval depression 29. Second, they insure that the end piece C will be properly centered within the depression, as it is usually desired that there shall be a slight clearance between the end piece and the depression in the forming member, and without the engagement of the notches 73 with pins 71, the end piece might be glued to one side or the other of the side walls of the box and not be symmetrically arranged as desired.

At station 2, the operator inserts the paperboard band B into the forming member at the front of the machine. The series of flaps F will have been folded previously so as to extend substantially at right angles to the walls of band B. This folding or pre-breaking of the flaps around the score line *s* adjacent their base line may be performed by hand or with the use of the folding machine described in our copending application for patent Serial No. 367,418 filed July 13, 1953. The operator at station 2 also manipulates the controls 47 and 66 for actuation of the mechanism at station 4, the operation of which will be described when we come to the discussion of the steps performed at station 4.

The operator at station 3 inserts the inner end piece C, to which glue will have been applied over the peripheral area which will come in contact with flaps F. If desired glue may also be applied at one or more points toward the center of this end piece where it may be pressed into contact with outer end piece A.

We come now to the operations performed at station 4 by the mechanism controlled by the operator at station 2. Latch 39 will be resting in notch 42 of indexing lock 38, and we begin with the parts in the position shown in Fig. 1. Inner and outer end pieces A and C and paperboard band B are in place in the forming member 28. The operator now actuates control 66 so that air is exhausted from the lower end of air cylinder 31 while air under pressure enters the upper end of this cylinder through the line 63. This drives piston rod 59 downwardly, carrying with it pressure plate 32 and allowing guide ring 30 to descend. Guide fingers 52 gather the open end of paperboard band B within the confines of the guide ring as the guide ring approaches the position shown in Fig. 3. During the last part of this action the guiding effect of fingers 52 is supplemented by the flaring opening 51 of the guide ring itself and the inclined edges 70

of the fingers 67. When the fingers 67 come to rest on the upper edge of the band B, downward movement of guide ring 30 ceases. In this initial position of rest of the guide ring 30, pressure plate 32 is about to enter within band B, the band having been accurately shaped to permit such entry with close tolerances around the periphery of the pressure plate as is essential in order to apply pressure effectively over the area of flaps F.

Further downward movement of piston rod 59 carries pressure plate 32 within the box, fingers 67 passing through the slots 68 of the pressure plate. The pressure plate then travels to the bottom of the box and applies pressure on the glued end pieces A and C for a matter of five seconds or so. Meanwhile the operators at stations 1, 2 and 3 are repeating the cycle. Next the operator at station 2 reverses the control 66, bringing the parts into the position shown in Fig. 1. He then depresses the operating finger 47, releasing latch 39 from indexing lock 38, and grasping one of the handles 49, rotates the table 90° in the direction of the arrow D (Fig. 2) bringing the next indexing lock 38 into engagement with latch 39. Thereupon the operator at station 1 removes the box which has just been completed at station 4.

The machine may be adapted to handle other shapes and sizes of boxes, and covers, by changing the forming members, guide ring and pressure plate for others of the proper size and shape. For example, in Fig. 12 is shown a forming member 28' in which is formed an octagonal opening 29', and which has a pair of positioning pins 34' arranged to fit the openings 37 of turret table 19. This shape of forming member may be used where the machine is to be applied for setting up and finishing boxes or covers of octagonal shape. It is merely necessary to lift out the forming members 28 and replace them with forming members 28'. Guide ring 30 and pressure plate 32 likewise would be removed and replaced with other members shaped for the octagonal box.

Stops 74 are adjustably mounted on the rods 26. These stops are positioned to come to rest on the upper ends of the sleeves 25 just as the parts reach the position shown in Fig. 3 and prevent the fingers 67 of the guide ring 30 from damaging the upper edge of the paperboard band, which might otherwise occur upon impact.

In Fig. 11 we have indicated the formation of a cover for the box shown in the other views. Because the cover band is relatively shallow it is generally unnecessary to provide a guide ring. Also, in forming the covers, beam 24 or the air cylinder 31 may be lowered to shorten the stroke of the pressure plate 32.

The terms and expressions which we have employed are used in a descriptive and not a limiting sense, and we have no intention of excluding such equivalents of the invention described, or of portions thereof, as fall within the purview of the claims.

We claim:

1. A machine for setting up and finishing paperboard hat boxes and the like from flat-folded blanks which comprises a forming member having a depression to receive a flat end piece and to receive and shape the base of a continuous paperboard band, a guide ring, means for producing relative movement between the paperboard band and the guide ring to cause the guide ring to surround and shape the paperboard band at its open end, a pressure plate shaped to conform closely with the inner walls of the shaped band and arranged to pass through said guide ring while the guide ring holds the open end of the paperboard band in position to receive the pressure plate within it, and means for producing relative movement between the forming member and pressure plate to bring the pressure plate within said depression of the forming member, said guide ring having fingers for engagement with the inside of the open end of the paperboard band and said pressure plate having slots in its periphery through which slots said fingers pass when the pressure plate passes through the guide ring and enters the open end of the paperboard band.

2. A machine for setting up and finishing paperboard hat boxes and the like from flat-folded blanks which comprises a forming member having a depression to receive a flat end piece and to receive and shape the base of a continuous paperboard band, pins resiliently supported within said depression of the forming member for engagement with alignment notches in said end piece, a guide ring, means for producing relative movement between the paperboard band and the guide ring to cause

the guide ring to surround and shape the paperboard band at its open end, a pressure plate shaped to conform closely with the inner walls of the shaped band and arranged to pass through said guide ring while the guide ring holds the open end of the paperboard band in position to receive the pressure plate within it, and means for producing relative movement between the forming member and pressure plate to bring the pressure plate within said depression of the forming member.

10 3. A machine for setting up and finishing paperboard
hat boxes and the like from flat-folded blanks which com-
prises a forming member having a depression to receive
a flat end piece and to receive and shape the base of a
continuous paperboard band, a guide ring, means for
15 producing relative movement between the paperboard
band and the guide ring to cause the guide ring to sur-
round and shape the paperboard band at its open end,
a pressure plate shaped to conform closely with the inner
walls of the shaped band and arranged to pass through
20 said guide ring while the guide ring holds the open end
of the paperboard band in position to receive the pressure
plate within it, and means for producing relative move-
ment between the forming member and pressure plate to
bring the pressure plate within said depression of the
25 forming member, said guide ring and pressure plate being
mounted for movement together until the guide ring sur-
rounds and shapes the paperboard band at its open end,
said pressure plate then being movable a further distance
with the guide ring stationary.

30 4. A machine for setting up and finishing paperboard
hat boxes and the like from flat-folded blanks which com-
prises a forming member having a depression to receive
a flat end piece and to receive and shape the base of a
continuous paperboard band, a guide ring, means for pro-
35 ducing relative movement between the paperboard band
and the guide ring to cause the guide ring to surround
and shape the paperboard band at its open end, a pres-
sure plate shaped to conform closely with the inner walls
of the shaped band and arranged to pass through said
40 guide ring while the guide ring holds the open end of the
paperboard band in position to receive the pressure plate
within it, and means for producing relative movement
between the forming member and pressure plate to bring
the pressure plate within said depression of the forming
45 member, said guide ring being freely suspended from the
pressure plate for movement into position surrounding
and shaping the paperboard band for the pressure plate
to enter the open end thereof and pass into said depres-
sion of the forming member.

50 5. A machine for setting up and finishing paperboard
hat boxes and the like from flat-folded blanks which com-
prises a forming member having a depression to receive a
flat end piece and to receive and shape the base of a con-
tinuous paperboard band, a guide ring, means for pro-
55 ducing relative movement between the paperboard band
and the guide ring to cause the guide ring to surround and
shape the paperboard band at its open end, a pressure
plate shaped to conform closely with the inner walls of
the shaped band and arranged to pass through said guide
60 ring while the guide ring holds the open end of the paper-
board band in position to receive the pressure plate with-
in it, and means for producing relative movement be-
tween the forming member and pressure plate to bring
the pressure plate within said depression of the forming
65 member, said guide ring having fingers for engagement
with the outside of the open end of the paperboard band
adjacent the fold lines thereof to gather the open end
within the confines of the guide ring as the guide ring ap-
proaches its position surrounding and shaping the paper-
70 board band at its open end.

6. A machine for setting up and finishing paperboard hat boxes and the like from flat-folded blanks which comprises a forming member having a depression to receive a flat end piece and to receive and shape the base of a continuous paperboard band, a guide ring, means for producing relative movement between the paperboard band and the guide ring to cause the guide ring to surround and shape the paperboard band at its open end, 75 a pressure plate shaped to conform closely with the inner walls of the shaped band and arranged to pass through said guide ring while the guide ring holds the open end of the paperboard band in position to receive the pressure plate within it, and means for producing relative 80 movement between the forming member and pressure 85

plate to bring the pressure plate within said depression of the forming member, said guide ring having fingers for engagement with the inside of the open end of the paperboard band and fingers for engagement with the outside of the open end of the paperboard band.
